Primary Examiner — Stacia Cadmus(74) *Attorney, Agent, or Firm* — Pearne & Gordon LLP(57) **CLAIM**

The ornamental design for a wheel, as shown and described.

DESCRIPTION

FIG. 1 is a perspective view of my new invention;
FIG. 2 is a front view thereof;
FIG. 3 is a rear view thereof; and,
FIG. 4 is a side view thereof, with the illustrated portion of the
wheel being symmetrical about a central axis.
The broken lines shown in the drawings illustrate portions of
the wheel that form no part of the claimed design.
